UNITED STATES PATENT OFFICE

2,564,186

ROTARY BASKET DISHWASHER AND LIQUID RECIRCULATING AND STRAINING MEANS THEREFOR

Leslie W. Benck, Moline, Ill., assignor to Deacon Products, Incorporated, Moline, Ill., a corporation of Illinois

Application December 14, 1945, Serial No. 634,949

2 Claims. (Cl. 134—147)

1

My present invention relates to apparatus for washing dishes and the main objects thereof are the provision of improved apparatus for washing dishes; the provision of simplified apparatus for the cleaning of soiled dishes; the provision of apparatus for the purpose stated which is inexpensive to manufacture and is efficient in use; and such further objects, advantages, and capabilities as will hereinafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 represents a horizontal section taken substantially along the plane indicated by the line 1—1, Fig. 2;

Fig. 2 represents a vertical section with parts shown fragmentarily;

Fig. 3 represents a vertical section approximately along the plane indicated by the line 3—3, Fig. 1; and

Fig. 4 represents a broken vertical section taken substantially along the plane indicated by the line 4—4, Fig. 1.

Reference will now be made in greater detail to the annexed drawings for a more complete description of this invention. The working parts of this construction are enclosed in a housing 1 and comprise the tub 2, the motor 3, and the pump 4. On the shaft of the motor there is a belt pulley 5 which is connected by a belt 7 to the pulley 6 mounted on the shaft 8 of the pump. On the inner end of this shaft 8 is an impeller 9 which withdraws water from the tub 2 and forces it around the pipe 10 and back into the tub 2 in a direction to engage the edges of plates, saucers, and the like, stood up in the basket 11. As shown in the drawings, the inlet end 12 of the fluid conduit is large and permits free access of water thereto, drawn in by the pump 9. The outlet end of the conduit 10 is elongated in a vertical direction but compressed in a direction at right angles thereto. Therefore, rotation of the impeller 9 forces the washing fluid through the conduit at an increasing rate and out against the dishes with considerable velocity.

A second pulley, indicated at 13, is mounted on shaft 8 and is connected to a pulley 14 by

16 a belt 15. The pulley 14 is carried by a shaft 16 which has a pinion 17 at its inner end. The pinion 17 cooperates with a ring gear 18 on the under side of the basket 11 in rotating the basket 19 which is suspended on a plurality of pulleys 19 carried by the inner wall of the tub 2. The basket 11 comprises a plurality of rings 20, 21, 22 to which are secured a plurality of outwardly extending wires 23. These wires are connected 10 at their inner ends to a ring 25, comparable to rings 20, 21, 22. From the rings 23 and 25 rise a series of wires 24. The upper ends of these upright wires are connected to a ring 26 which forms an outside upper boundary of the basket. 15 The upper outwardly extending wires 23 are comparable to the lower wires of the basket which, together with the rings 20, 21, 22 and 25, form compartments for the reception of flattish dishes, such as plates, saucers, and the like. Cups and 20 other hollow ware can be placed on top of these upper wires 23, with their hollow sides facing the water stream so that they can be washed by water forced against them.

At the center of the tub is a cup 27 in which 25 is supported a wire screen 27a having an opening facing the stream of water emerging from the pipe 10 and striking the dishes in the basket 11. The water which washes particles of food from the dishes carries them into the screen 26 which strains them out of the water, allowing 30 them to collect in the cup 27 from which they may be removed. A valve controlled pipe 29 is provided for withdrawing the wash water from the tub 2. The washed dishes may be put out 35 on the draining board 28 from which the wash water runs back into the tub 2. The tub 2 is shown as being provided with a cover 30.

Briefly stated, the operation of the machine 40 is as follows. The dishes are placed in the basket 11 and hot water is put into the tub 2 until it covers the exit from the tub into the pump. The motor is then started and this drives the impeller 9, forcing the water out through the end of the water-carrying pipe 10 and against 45 the dishes in the basket 11. This basket is rotated slowly by the pinion 17 driven indirectly from the motor 3. After the dishes are sufficiently washed, the motor is stopped and the dishes are removed from the basket and placed 50 on the draining board.

It will of course be understood that the specific 55 description of structure set forth herein may be departed from without departing from the spirit of this invention as set forth herein and in the annexed claims.

Having now described my invention, I claim:

1. In a structure for the purpose stated, a fixed container for the reception of a washing fluid, spaced supporting rollers mounted therein and adapted to rotate on their axes, free from contact with the bottom of the container, a basket supported on said rollers and adapted to rotate in said container, mechanism for rotating said basket in said container, said basket having an unobstructed central opening, a non-rotatable netting trap for detached particles centrally located in said container within said central opening and extending upwardly through said opening, and a pump having an inlet pipe and an outlet pipe connected to the container at separated points to withdraw the washing fluid therefrom and return it thereto at a velocity at least as great as the velocity of withdrawal, said trap having a longitudinally extending slot in its wall facing the return end of the outlet pipe.

2. A washing machine comprising, in combination, a container for articles to be washed, an article-holding basket supported therein for free rotation on rotatable means, said basket having an unobstructed opening in the bottom thereof, a fixed screen extending upwardly from the bottom of the container through the opening in the bottom of the basket and having a vertical longitudinal slot in the wall thereof, the basket being rotatable about the screen and being provided with

15

compartments for the reception of articles to be washed, said compartments being arranged approximately tangentially to the outer surface of the screen, means for withdrawing washing fluid from the container and returning it thereto at a point along the lateral wall of the container, remote, in the direction of rotation of the basket, from the point of withdrawal, and means for causing operation of the withdrawing means, said last named means also causing rotation of the basket about the screen, the slot in the screen facing the water-return opening.
